US00D700228S

(12) **United States Design Patent**
O'Neill et al.

(10) **Patent No.:** **US D700,228 S**
(45) **Date of Patent:** **** Feb. 25, 2014**

(54) **OPTICAL COMPONENT MOUNT**

(71) Applicant: **Premier Systems USA, Inc.**, Huntington Beach, CA (US)

(72) Inventors: **Patrick D. O'Neill**, Huntington Beach, CA (US); **Chong Pak**, Lakewood, CA (US)

(73) Assignee: **Premier Systems USA, Inc.**, Huntington Beach, CA (US)

(**) Term: **14 Years**

(21) Appl. No.: **29/452,461**

(22) Filed: **Apr. 16, 2013**

Related U.S. Application Data

(62) Division of application No. 29/443,884, filed on Jan. 23, 2013, which is a division of application No. 29/409,978, filed on Dec. 30, 2011, now Pat. No. Des. 678,379.

(57) **CLAIM**

The ornamental design for an optical component mount, as shown and described.

DESCRIPTION

FIG. 1 is a front, top, and left side perspective view of an optical component mount;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear, bottom, and right side perspective view thereof;

FIG. 9 is a front, bottom, and right side perspective view thereof; and,

FIG. 10 is a front, bottom, and left side perspective view thereof.

The features illustrated in phantom line form no part of the claimed design.

1 Claim, 10 Drawing Sheets
